UNITED STATES PATENT OFFICE.

SARAH JANE SHIELS, OF NEW YORK, N. Y., ASSIGNOR TO THE BUTTERICK PUBLISHING COMPANY, (LIMITED,) OF SAME PLACE.

DESIGN FOR A LADY'S WALKING-SKIRT.

SPECIFICATION forming part of Design No. 15,132, dated July 8, 1884.

Application filed May 23, 1884. Term of patent 15 years.

To all whom it may concern:

Be it known that I, SARAH JANE SHIELS, of the city, county, and State of New York, have invented and produced a new and original Design for a Pattern of a Lady's Walking-Skirt, numbered 9,278; and I do hereby declare that the engraved prints accompanying this specification convey to any one accustomed to using paper patterns a clear understanding of how to a garment made up by the pattern will appear.

The design shows a round walking-skirt with draperies. The right front-drapery displays draping plaits in its front and back edges, and an increase of depth toward the back edge; the shorter left side-drapery dis-

plays draping plaits in its front and back edges, and appears to underlap the right front-drapery at its front edge; and the fall back-drapery exhibits draping plaits in its front edges, loopings at the center, and a deeply pointed effect at the right side.

What I claim as my invention, and desire to secure by Letters Patent, is—

The design for a lady's walking-skirt, as shown in the engraved prints accompanying this specification.

SARAH JANE SHIELS.
